UNITED STATES PATENT OFFICE.

HARRY E. KERR, OF CLEVELAND, OHIO.

GAS BURNER.

Application filed December 29, 1924. Serial No. 758,616.

To all whom it may concern:

Be it known that I, HARRY E. KERR, a citizen of the United States, and residing at Cleveland, in the county of Cuyahoga and State of Ohio, have invented certain new and useful Improvements in Gas Burners, of which the following is a specification.

This invention relates to an improvement in gas burners, and more particularly to jet burners of the type and kind disclosed in my application for Patent Serial No. 720,558 filed June 17, 1924. In the present invention, my general object is to group the jets in a particular way to gain the maximum heating effects within a given area without causing malfunction in mixing and burning operations at any one of the jets or co-acting pairs of jets, and a further object is to bring the separate sheets or columns of flame produced by each pair of jets into close proximity both radially and tangentially in a circular burner to permit it to be used very effectively in a cylindrical heater, for example, a water heater having a plural number of concentric water circulating coils supported centrally above the burner, all substantially as hereinafter shown and described and more particularly pointed out in the claims.

In the drawings accompanying this application, Fig. 1 is a top view of one form of gas burner embodying my invention, and Fig. 2 is a vertical section thereof on line 2—2 of Fig. 1. Fig. 3 is a top view of a modification of the invention, and Fig. 4 a side elevation thereof.

In certain types of water heaters containing water circulating and heating coils or equivalent elements it is desirable to concentrate a large amount of heat in a small circumscribed space and area, and the present burner is designed to jet streams of air and gas into confluence at a plurality of places above the burner to produce a plural number of vertical sheets or columns of flame adapted to burn independently but in such close proximity to each other that the combined flames will be uniformly applied to the heating elements superposed above the burner. In some instances separate sets of coils or heating elements of different diameters are concentrically arranged, and the

present burner is especially serviceable in that connection in distributing the flame to both the inner and outer coils or heating elements. 55 Thus, referring to Figs. 1 and 2, the circular burner shown therein comprises a hollow cast metal body or ring 2 having a small hub-portion 3 at its center and hollow arms or spokes 4 extending in opposite directions 60 from this hub to the ring. An open boss 5 at the bottom of the central hub has an internal screwthread to permit a gas supply pipe 6 to be connected therewith, and the burner may be solely supported on this pipe 65 if necessary. The top of hub 3 is of conical shape or formed with reversely-inclined flat faces 7 to permit a series of gas jets or nozzles 8 to be seated thereon at an angle of approximately forty-five degrees, and these 70 nozzles extend radially outward toward corresponding nozzles 8' seated in reversely-inclined position on flat faced bosses 9 and 9" on ring 2. Each nozzle has a screw-threaded extension 10 at its base which is 75 formed with a gas intake cavity 11 terminating in a short gas orifice 12 of small diameter axially co-incident with the longer main bore 13 of the nozzle. One or more lateral openings 14 in the side wall of the 80 base portion of the nozzle admit air to bore 13 and this air is discharged with the stream of gas passing through the nozzle, the combined stream of air and gas coming into forcible impact and commingling with a 85 similar stream of air and gas discharged at the same high velocity from the reversely-inclined companion nozzle axially opposite thereto. As a result a spreading sheet of flame is maintained vertically at right angles 90 to the axis between and above the mouth ends of each co-acting pair of nozzles, and where a plurality of pairs of nozzles are disposed radially of the burner as described a plural number of sheets or columns of 95 flame are produced at spaced intervals radially of the burner approximately midway of the center and the outer boundaries of the burner.

An additional number of spreading sheets 100 of flame are produced at spaced intervals above ring 2 by a second group of jets or nozzles 8", the separate sheets of flame being caused to spread radially of the burner to-

ward the other sheets of flame inside of the ring or circle by arranging the inclined jets or nozzles in pairs on tangential lines to the circle. To that end ring 2 is provided 5 with raised bosses 9' at its top having flat inclined faces to seat the nozzles, each boss having at least two nozzles extending at an inclination in opposite directions or radially therefrom toward reversely-inclined nozzles 10 on the adjoining bosses on ring 2. In the burner shown in Fig. 1, two of the bosses marked 9'' are placed diametrically opposite each other on ring 2 at right angles to the hollow arms 4, and each of these two bosses 15 mount or carry three nozzles, the central nipple 8 on each co-acting with a companion nipple extending radially of the burner from hub 3, and the other two nozzles 8'' extending from the opposite sides of the boss 20 toward companion nozzles on the bosses marked 9' on the same ring. Bosses 9' mount only two nozzles, and it may be observed that the co-acting nozzles 8'' which 25 project toward each other and the median line of the burner which passes through the hub and hollow arms 4 cause two streams of gas to commingle and spread directly above the bosses 9 which carry only single nozzles 8' extending radially toward companion nozzles on hub 3. As thus related 30 the separate pairs of nozzles are permitted to function perfectly without interference with each other, while obviously closely grouped together, and the commingled streams of air and gases are also permitted 35 to spread and burn freely without objectionable interference or results. In that connection it should be understood that each pair of nozzles discharge a predetermined 40 amount of gas and air into confluence which burns as a hollow column of flame of substantial dimensions. Apparently a certain percentage of unconsumed gases travel upwardly within the hollow body of flame 45 until all of the gas is consumed, the air which is entrained with the gas at each nozzle of the pair together with the surrounding air being adequate to produce perfect combustion at remote points from the 50 tips or mouth ends of the nozzles when the burner is operating at full force, that is, when the gas is turned on at maximum pressure. On the other hand when the gas is turned down and the pressure is reduced 55 to a minimum the gas will burn blue in color in the form of a small bead at the mouth of each nozzle.

In Figs. 3 and 4, I show a modified form 60 of burner which is essentially the same as the burner described, the main differences being that ring 2' is of larger diameter and a larger hub 3' of ring shape is involved. Three hollow arms or spokes 4' are also used instead of two, and the supply of gas is taken 65 in through a lateral extension or boss 5'

instead of at the center. Obviously, this form of burner permits a larger number of jets or nozzles to be grouped together on radial and tangential lines with similar operating effect and result but with greater 70 heating capacity, comparing the two burners, unit for unit.

What I claim, is:

1. A gas burner, comprising a hollow ring having a circular hollow central part 75 and a plurality of complementary pairs of gas nozzles mounted radially in reversely-inclined position upon said ring and central part.

2. A gas burner, comprising a hollow ring having a hollow hub and hollow arms, a plurality of gas nozzles arranged in pairs in reversely-inclined position upon said ring, and a plural number of gas nozzles mounted 80 in reversely-inclined relation in pairs opposite each other upon said hub and ring. 85

3. A gas burner, comprising a hollow ring having co-acting pairs of reversely-inclined gas nozzles extending upwardly 90 therefrom at spaced intervals tangentially of the ring, a plurality of gas nozzles at the center of said burner extending radially outward and inclined upwardly toward said ring, and a plurality of gas nozzles extending radially inward from said ring toward the 95 central nozzles.

4. A gas burner, comprising a hollow gas ring having pairs of gas nozzles extending upwardly at an inclination toward each other 100 on the ring and other nozzles extending toward the center of the ring, and still other gas nozzles at the center of the ring extending upwardly and outwardly at an inclination toward companion nozzles on the 105 ring.

5. A gas burner, comprising a hollow ring and a central hollow hub in gas distributing connection, a plurality of gas nozzles extending radially outward from said hub, companion gas nozzles extending radially inward from said ring opposite said hub nozzles, and a plurality of pairs of gas nozzles mounted in reversely-inclined gas 110 converging relation upon said ring on lines 115 angularly related to said radially arranged nozzles.

6. A gas burner, comprising a hollow ring having raised bosses thereon and formed with a hollow central hub in gas distributing 120 connection with said ring, a plurality of gas nozzles radially mounted upon said hub and extending upwardly at an inclination toward the bosses on said ring, a plurality of gas nozzles mounted upon said bosses and extending upwardly at an inclination toward each other in pairs annularly of the ring, and separate gas nozzles on a number of said bosses extending inwardly and upwardly toward the nozzles upon said hub. 125

7. A gas burner, comprising a hollow 130

ring having a central hollow hub and hollow spokes connecting said hub and ring, a plurality of pairs of gas nozzles mounted in reversely-inclined position at spaced intervals upon said ring and arranged to bring separate streams of gas into confluence above the ring, and a plurality of pairs of gas nozzles mounted in reversely-inclined position radially of said hub and ring and arranged to bring separate streams of gas into 10 confluence at isolated places between said hub and ring.

In testimony whereof I affix my signature.
HARRY E. KERR.
